(57) CLAIM

The ornamental design for exercise leggings, as shown and described.

DESCRIPTION

FIG. 1 is a front perspective view of exercise leggings employing an ornamental design in accordance with the present invention;

FIG. 2 illustrates a front view thereof;

FIG. 3 illustrates a back view thereof;

FIG. 4 illustrates a right view thereof;

FIG. 5 illustrates a left view thereof;

FIG. 6 illustrates a top view thereof; and,

FIG. 7 illustrates a bottom view of thereof.

The broken line portions of FIGS. 1-7 are included to show unclaimed subject matter only and form no part of the claimed exercise leggings.

The dotted surfaces of the exercise leggings compared to the other surfaces of the exercise leggings represent a contrast in appearance.
